UNITED STATES PATENT OFFICE

GUSTAF A. JOHNSON, OF NEW BEDFORD, MASSACHUSETTS, ASSIGNOR TO JOHN I. PAULDING, INC., OF NEW BEDFORD, MASSACHUSETTS, A CORPORATION OF MASSACHUSETTS

ELECTRIC SWITCH

Application filed April 30, 1929. Serial No. 359,259.

This invention relates to electric switches and more particularly to that type generally known as snap switches in which the circuit is closed or opened by a rocker member actuated by a spring controlled by a snap or toggle lever.

The main object of the invention is the provision of a switch which is efficient in operation, which is simple and compact in construction, employing a minimum number of parts and which may be made and assembled rapidly and at a low cost.

Another object of the invention is the provision of a switch construction in which the insulating body is utilized as bearings for the rocker member and toggle lever thereby eliminating the necessity of providing metallic bearings for such purpose.

Other objects of the invention will be pointed out hereinafter.

In the accompanying drawings illustrating one embodiment of my invention, Figure 1 is a plan view of a single pole switch constructed in accordance therewith; Fig. 2 is a similar view of the same with the cap or cover removed; Fig. 3 is a vertical central sectional view on line 3-3 in Fig. 1; Fig. 4 is a sectional view on line 4-4 in Fig. 2; Fig. 5 is a sectional view on line 5-5 in Fig. 2; Fig. 6 is a plan view of the rocker member in flat form before the contact portions are bent upwardly; Fig. 7 is a view in perspective of a fixed contact and Fig. 8 is a view in perspective of the binding screw portion of a fixed contact.

In the drawings illustrating the invention there is shown a single pole switch but the invention is capable of embodiment in other forms of switches by structural modifications which would be apparent to one skilled in the art.

Referring to the drawings 10 indicates an insulating body which may be of any suitable shape but as shown is circular and which may be made of porcelain or any other suitable insulating material. Centrally located in the top or inner face 12 of the body is formed a deep recess or chamber 14 in which is mounted a rocker member 16 for bridging a pair of fixed contacts 18 projecting into

the recess. The rocker member is preferably stamped from sheet metal and is U-shaped in general form having its two ends 20 (Fig. 6) turned outwardly to form journal portions fitting loosely in grooves 22 in the insulating body. The latter thereby serves as bearing surfaces eliminating the necessity of providing special parts for pivotally supporting the rocker member. To insure a perfect contact the rocker member when stamped out has two projections or tongues 23 (Fig. 6) formed at opposite ends of its bottom portion which projections or tongues are later bent upwardly for engaging the two fixed contacts flatwise (Fig. 5).

The two contacts are arranged at one end of the recess but in separated relation and in a position to be engaged and bridged by the rocker member when that member is rocked to that end. The contacts may be of any suitable form but as shown each comprises a contact blade designated as 18 projecting into the recess and having one end in the form of a square 24 turned laterally and having a central hole 26 (Fig. 7) for securing it to the inner face of the body 10 adjacent the recess by a screw 28 inserted from the bottom or outer face of the body through a bore 30 which is enlarged at its outer end 32 for receiving the head of the said screw. A small angle piece 34 (Fig. 8) having a threaded hole 36 for a binding screw 38 and a threaded hole 40 for the end of the screw 28 is mounted on the squared end of each contact, adjacent which is a bore 42 through the insulating body for the lead wire to the binding screw. To prevent any possibility of shortcircuiting between the contacts the blades of the contacts are countersunk in the end wall of the recess 14 so that there is between them an intervening section of the insulating body.

For actuating the rocker member a helical spring 44 is loosely mounted thereon, one end of the spring fitting around an upwardly turned lug 46 formed on the bottom of the rocker member and the other end is hooked through a hole 48 in a plate 50 set in a toggle lever 52 of insulating material. The toggle lever is pivotally mounted on a pin 54 journalled in two upright lugs or projections

56 formed on the inner face of the insulating body and integral therewith and positioned on opposite sides of said recess. The pin 54 passes through the plate 50 so that the insulating material of the toggle lever is relieved of all strain. Since the rocker member and the toggle lever are pivotally mounted and the spring 44 is under compression at all times the tendency of the top end of the spring is to assume an off center position and to throw both the toggle lever and rocker member to one side or the other in an opposite direction (Fig. 3). When the toggle lever is moved to its opposite position the top end of the spring is carried across the plane of the rocker member and thereupon throws the rocker member in the same direction that the toggle lever is moved and the compression of the spring carries them both as far as they can go and holds them there. The movement of the rocker member is limited of course by the walls of the recess and the movement of the toggle member by the oblique edges 58 of the plate 50 engaging the top surface of the insulating body. The toggle lever has shoulder portions 60 which may be marked on their outer surfaces with the words "On" and "Off" respectively to indicate a closed circuit and an open circuit respectively.

For covering the switch mechanism a circular cap or cover 64, having a rectangular opening 66 through which the toggle lever projects is mounted on the insulating body 35 10 and the flange 68 of the cap fits into an annular rim portion 70. The flange of the cap may be insulated from the switch mechanism by an interior band 72 of paper or other insulating material. For locking the cap in place, the flange thereof is provided with two interior oppositely disposed locking projections 74 (Fig. 4) adapted to interlock with oppositely faced locking projections 76 on the two lugs. To remove the cover the flange thereof is pressed inwardly at opposite points between the locking projections which pressure throws outwardly the portions of the flange carrying the locking projections and disengages them from the projections on the lugs whereupon the cap may be lifted off. To return the cap it is merely pressed in place until the flange locking projections snap over the lug projections. For fastening the switch in a switch box or 55 in place the insulating body is provided with a pair of screw holes 80 having shoulders 82 against which abut the heads of the fastening screws.

The assembling of a switch constructed in accordance with my invention is a very simple matter. The fixed contacts and the angle pieces carrying the binding screws are mounted in position and fastened by the two screws 28. The rocker member is then 65 dropped into the recess with its journalled

portions in the grooves and after the actuating spring is connected to the toggle lever by passing its upper end through the hole in that member the latter is then adjusted in position by dropping the lower end of the spring over the lug 46 on the rocker member and the assembling of the switch is completed by pushing the pin through the lever. It will be observed that in this assembling only two screws are required, those being used for 70 holding the contacts in position. The rocker member is loosely mounted in the recess and is held in its bearings by the downward pressure exerted by the spring which is at all times under compression. The pin 54 inserted 75 through the lugs on the insulating body holds the parts in assembled relation. By utilizing the insulating body as bearing surfaces for the journals in the rocker member, I avoid the provision of metal bearings therefor 80 since I have found that the insulating body will serve this purpose equally as well as metal bearings. The walls of the recess limit the throw of the rocker member and therefore act as stops to limit the movement of that 85 member in both directions. By using the lugs molded in the insulating body as supports for the spindle, I eliminate the necessity of providing a frame or other metal part for holding the toggle member. The result is that 90 the switch mechanism is made up of a very few parts which can be assembled very quickly and expeditiously which reduces the cost of construction and assembly of the switch to a minimum without at all interfering with its efficiency or durability.

In the operation of the switch, when the toggle lever is thrown over from one position to the other that end of the actuating spring connected to it is thrown across the 105 plane of the rocker member, the spring being further compressed thereby, so that the force of the spring is exerted upon the other side of the rocker member to throw it in the same direction that the toggle lever is moved. The actuating spring being under compression at all times holds the rocker member and toggle lever either in a closed or an open position dependent upon the direction in which the toggle lever has been moved.

It is to be understood that the form of the invention herein shown and described is merely for purpose of illustration since the invention may be embodied in various other forms of construction within the scope of 110 the following claims.

What I claim is:

1. An electric switch having, in combination, a one-piece recessed insulating body having a pair of integral projecting lugs, a pair of fixed contacts in said recess, a rocker member loosely mounted in said recess for bridging said contacts, a spring for actuating said rocker member and a toggle lever pivotally 125

- mounted in and between said lugs for actuating the spring.
2. An electric switch having, in combination, a one-piece insulating body provided on one face with a central recess and a pair of integral projecting lugs, a pair of fixed contacts mounted on said body in separated relation and projecting into said recess, a rocker member loosely mounted in said recess for bridging said contacts, a spring for actuating said rocker member, a toggle lever pivotally mounted in said body for actuating said spring and a cover adapted to interlock with said lugs.
- 15 3. An electric switch having, in combination, an insulating body having two integral projecting lug portions on its inner face at opposite sides thereof, a pair of fixed contacts mounted on said body in separated relation, a rocker member journalled in said insulating body for bridging said contacts, a spring for actuating said rocker member, a toggle lever pivotally mounted in said lugs for actuating said spring and a cover for said switch adapted to interlock with said lugs.
4. An electric switch having, in combination, an insulating body having a pair of integral projecting lug portions, a pair of fixed contacts mounted on said body in separated relation, a rocker member loosely journalled in said insulating body for bridging said contacts, a spring for actuating said rocker member, a toggle lever pivotally mounted in said insulating body for actuating said spring and a cover for said switch having a resilient flange adapted to interlock with said lugs.
5. An electric switch having, in combination, a one-piece insulating body having a pair of integral projecting lugs and a recess there between, a pair of fixed contacts projecting into said recess in separated relation, a rocker member mounted in said recess and journalled in said insulating body for bridging said contacts, a spring for actuating said rocker member, a toggle lever pivotally mounted on and between said lugs for actuating said spring and a cover mounted on said body; said cover having a flange provided with means interlocking with said lugs—and said flange being resilient to permit interlocking of said interlocking means when pressure is exerted upon said flange intermediate said interlocking means.
- 55 6. An electric switch having, in combination, a one-piece insulating body having on its inner face a pair of integral projecting lugs spaced apart and a recess there between, a pair of fixed contacts projecting into said recess in separated relation, a rocker member mounted in said recess and journalled in said insulating body for bridging said contacts, a spring under compression at all times for actuating said rocker member and a toggle lever pivotally mounted on and between said lugs for actuating said spring.
7. An electric switch having, in combination, a one-piece insulating body provided with a recess in one face and two integral projecting lug portions, one on each side of said recess, a pair of fixed contacts projecting into said recess in separated relation, a rocker member journalled in said insulating body for rocking movement in said recess to bridge said contacts, a spring for actuating said rocker member and for holding it in its bearings and a toggle lever pivotally mounted on and between said lug portions for actuating said spring.
- 70 8. An electric switch having, in combination, a one-piece insulating body having a recess and projecting lugs, one on each side of said recess, a pair of fixed contacts, a rocker member journalled in grooves in said insulating body for rocking movement in said recess to bridge said contacts, a spring for actuating said rocker member and for holding said member in its bearings and a toggle lever mounted in and between said lugs for actuating said spring.
- 75 9. An electric switch having, in combination, a one-piece insulating body provided with a recess, a pair of fixed contacts in said recess, a U-shaped rocker member for bridging said contacts, said member being mounted in said recess and journalled in the side walls thereof, a spring for actuating said rocker member, said spring being under compression at all times to hold said rocker member in its bearings, and an operating member connected to one end of said spring for actuating the same.
- 80 10. An electric switch having, in combination, a recessed insulating body provided with a pair of projecting lugs, one on each side of said recess, fixed contacts in said recess, a rocker member mounted in said recess for bridging said contacts, a spring for actuating said rocker member, a toggle lever for actuating said spring and a cover for said switch; said lugs and said cover being provided with interlocking means to hold said cover in place.
- 85 11. An electric switch having, in combination, a one-piece recessed insulating body, fixed contacts in said recess, a rocker member mounted in said recess for bridging said contacts, said member being journalled in said insulating body, a spring for actuating said rocker member, means pivotally mounted in said insulating body for actuating said spring and a cover mounted on said body and provided with a suitable opening through which projects said spring actuating means, said cover and said insulating body being provided with interlocking means for holding said cover thereon.
- 90 12. An electric switch having, in combination, a one-piece recessed insulating body, a pair of fixed contacts mounted in said recess, a rocker member for bridging said contacts,
- 95 100 110 115 120 125 130

said member being loosely mounted in said recess and journaled in grooves in said insulating body, a spring for actuating said rocker member and a toggle lever pivotally mounted in said insulating body for actuating said spring, said spring being connected at one end to said lever and at its other end bearing against said rocker member to hold said member in its bearings.

10 13. An electric switch having, in combination, a one-piece insulating body having a pair of projecting lug portions and a central recess there between, a pair of fixed contacts in said recess, a rocker member loosely mounted in said recess for bridging said contacts, a spring for actuating said rocker member and for holding it in rocking position; a toggle lever pivotally mounted in and between said lug portions for actuating said 20 spring to rock said rocker member and a cover for said switch, said lug portions and said cover being provided with interlocking means for detachably holding said cover in place.

25 14. An electric switch having, in combination, a one-piece insulating body having a pair of projecting lug portions and a central recess there between, fixed contacts in said recess, a rocker member in said recess for bridging said contacts, an actuating spring, 30 a toggle lever mounted in and between said lug portions for operating said spring and a cover, said cover and said lug portions having interlocking projections for detachably holding said cover in place.

35 In witness whereof, I have hereunto set
my hand this 27th day of April, 1929.

GUSTAF A. JOHNSON.
